APPARATUS FOR STRINGING TENNIS RACKETS

Roy A. Sterns, Miami, Fla., assignor to The Roy Sterns Company, Cincinnati, Ohio, a corporation of Ohio

Application October 10, 1934, Serial No. 747,788

2 Claims. (Cl. 273—73)

This invention relates to a mechanical apparatus used to facilitate the stringing of lawn-tennis rackets.

It is well known to those versed in the art of tennis that the accomplishment of the desired results depends to a great extent on the perfection of the racket employed. This means that the stringing must be extremely tense and uniform, and that the frame must be held rigidly, and in an absolutely perfect longitudinal-horizontal plane. In the process of properly stringing a racket, the frame is subject to very severe strains, which have a tendency to distort or warp it. It is therefore essential, in order to attain the desired result, that the frame be rigidly secured in a perfect plane.

The equipment in common use in stringing lawn-tennis rackets provides a cumbersome embodiment that requires a rigidly fixed location, and is inconvenient to operate, being necessary to walk around the equipment as each string is inserted, and more or less inefficient.

The objects of the present invention are the provision of means for the purpose set forth, that embody a simple, durable, noncumbersome construction, and which is extremely convenient and efficient in operation.

With these objects in view the invention provides a rotatable racket-holder that facilitates the operation of the apparatus, economizing in time and labor in the manipulation, by eliminating the inconvenience incident to the operation of a fixed construction. The present embodiment enables the operator to work on all parts of the racket, in a sitting position, or without moving about. The racket is held securely on the rotatable holder, at the head and throat by clamping devices that in no way interfere with the stringing, so that individual strings may be inserted without any interfering obstacle. The racket is held on the rotatable member in a vise-like embodiment that insures the frame, under severe strains, against warping, or distortion in any degree from the correct plane. The rotating function of the holder is controlled by the manipulation of push-button means that automatically release and stop the movable member at the limits of a predetermined arc. In the present embodiment this arc is a semicircle.

The equipment is adjustable to the accommodation of any size racket. An important feature of the improved construction is the means for securely clamping the head and throat of the racket frame in the desired horizontal-longitudinal plane of alignment, while the

longitudinal adjustment of the curved throat clamp provides what is commonly known as a "billiard", enabling the racket to be strung taut and uniform.

This practical working apparatus can be made durable and efficient and at the same time be of exceptionally light weight and small volume, so that it can readily be confined in noncumbersome luggage for transportation, being small enough to be carried in an ordinary suitcase, and can be instantly and firmly installed for operation on any ordinary table or shelf without altering or damaging the furniture to which it is attached.

With the above-mentioned objects and advantageous features in view, the invention consists in the construction, an embodiment of which is shown in the drawings described in the specification, and pointed out definitely in the appended claims.

Figure 1 is a plan of the equipment, showing a racket contained therein, with a portion of the strings broken away. Fig. 2 is a side elevation. Fig. 3 is an end elevation of the throat end, and Fig. 4 an elevation of the head end of the equipment. Fig. 5 is a fragmentary longitudinal section (enlarged scale) on the central line through the curved throat support. Fig. 6 is a transverse central section in direction of arrow 6 in Fig. 2. Fig. 7 is a longitudinal-vertical section in line 7—7, Fig. 8. Fig. 8 is a plan of the equipment without the racket included. Fig. 9 is a transverse central section in direction of arrow 9, Fig. 2. Fig. 10 is a transverse section (enlarged) in line 8—8, Fig. 8. Fig. 11 is a fragmentary plan (enlarged) of a vise member, and Fig. 12 is an elevation of said vise member. Fig. 13 is a plan of an auxiliary "billiard" member that may be employed, and Fig. 14 is an elevation of said "billiard."

The present construction provides a base-member 1 adapted to be clamped to a table or other suitable support. A racket holder 2 is mounted on the base 1, pivotal connection being provided by the holder being journaled on a vertical bolt 3 fixed in the base 1, thereby adapting the holder to be rotated in a horizontal plane, the rotary movement of said holder being controlled by means which will hereinafter be described.

The racket holder provides vertical supports 4 and 5. The support 4 is rigid with the member 2 and registers with the head of the racket frame R, while the support 5 is longitudinally adjustable and registers with the curved throat

of said frame. The support 4 has a ledge 4a which fits the interior contour of the racket head, and the support 5 is provided with a ledge 5a, which is adapted to fit the interior 5 contour of the throat of the racket. The top faces of the ledges 4a and 5a are in a plane with the underside of the racket strings when a racket is positioned for stringing, thus while the ledges 4a and 5a provide positive locating 10 means for the racket frame, they do not interfere with the stringing.

Clamp elements 6 and 7 mounted respectively on vertical bolts 8 and 9 and carrying wing-nuts, coact with the members 4 and 5 to firmly 15 retain the racket on the holder. The co-acting functions of the fixed ledge 4a and the ledge 5a, on the adjustable support 5 provide a positive form fitting "billiard". While it is not a necessity, an auxiliary "billiard" 10 is anticipated, and under certain conditions it may be 20 deemed expedient to employ the auxiliary element and in such incidents it can readily be installed.

The means for controlling the rotation of the 25 holder member is best illustrated in Fig. 10, and will now be described. The base 1 has a boss 1a, which provides a bearing for the rotation of the member 2, said member 2 being provided with a boss 2a adapted to bear on the boss 1a. The boss 1a has a pocket 1b, which forms a housing for a spiral spring 1c and a plug cap 1d. The movable member 2 is provided with apertures 2b, which extend thru the boss 2a and are in an arc adapting them to 30 register with the pocket 1b. The apertures 2b form housings for push-buttons in the form of pin elements 2c and 2d. When the equipment is in a stationary condition, the pocket 1b is in registration with one of the apertures 2b and the plug 1d is forced into the aperture 2b by the action of the spring 1c, thereby locking the members against relative movement. Downward pressure on the pin 2c, acting on the plug 1d forces said plug to the bearing plane 35 of the bosses 1a and 2a, compressing the spring 1c, thereby permitting the movable member to be rotated a distance governed by the predetermined extent of the arc between the apertures 2b. When the pin 2d registers with the 40 pocket 1b the plug 1d freely enters the aperture under pressure of the spring 1c and again locks the members with the companion push-button idling.

The present embodiment provides for a reciprocating movement in an arc of 180 degrees. 45 Therefore, only two push-buttons are required, said push-buttons being located 180 degrees apart with a radius coincident with the radial distance of the pocket 1b. It will be clearly understood that the same general principle is 50 applicable in case more than two stops are desired, which could be accomplished by the arrangement of the required number of push-buttons operative in the same arc.

As an accessory to the apparatus, a vise is 55 embodied, the purpose of which is to accommodate or hold the racket after it has been properly strung, and to facilitate the process of

what is known as trimming, and which may be more or less elaborate, but not causing any stress on the frame.

In the present construction, the vise comprises a head 14 mounted on a stud bolt 15 carrying a winged-nut 15a bearing on the outer face of head 14. This provides for the gripping of the handle of a racket in the jaw formed between the member 14 and the element 2. Guide elements 16 are connected with 10 the head 14 and freely reciprocate in pockets 17 provided in the rotatable member.

In using the device the upper part is turned to compress the springs 11 and there locked. The members 5 and 4 are then adjusted to suit 15 the length of the racket to be strung, a billiard 10 being used for this purpose, if desired, by fitting the same on the upper ends of the bolts 8 and 9 as clearly shown in Figure 7. The gut is then run through the holes in the racket rim, 20 the racket and its support being turned end for end when desired. After the stringing is completed the racket is released and then its handle may be gripped between the members 14 and 2 as clearly shown in Figure 1, while trimming of 25 the gut is effected. Finally it is removed from the vise.

It will be understood that the apparatus admits of various changes in design and details of construction without departing from the 30 principles of the invention, and within the scope of the claims.

I claim:

1. In apparatus for stringing tennis rackets and the like, a base member, an elongated member mounted on the base member; a support on each end of the elongated member, each of said supports having an upstanding arcuate ledge fitting the interior contour of the end of a racket head resting on the horizontal part of 35 said support, means for adjustably mounting each of said supports for movement longitudinally of said elongated member for movement of the supports toward and from each other, bolts extending above the respective support, 40 and clamps on said bolts extending arcuately around the ends of a racket head held thereby to press said ends flat against the ledges and thereby to hold the racket from warping.

2. In apparatus for stringing rackets and the like, a base member, an elongated member mounted on the base member and provided at each end with an opening, a support on each end of the elongated member, said supports being adapted to engage the ends of a racket head, 55 a bolt for each support passing through a respective opening, each of said bolts extending above the respective support, each of said supports having an upstanding arcuate ledge fitting the interior contours of the ends of a racket head, said racket head resting on the horizontal parts of said supports, and clamps on said bolts extending arcuately around the ends of a racket head held thereby to press said ends flat on the supports and thereby to hold the racket 60 from warping.

ROY A. STERNS.
